UNITED STATES PATENT OFFICE.

JOSEF HRONECK, OF WORMS, GERMANY, ASSIGNOR TO FRIEDRICH HORN,
OF WORMS, GERMANY.

APPARATUS FOR COATING METALLIC ARTICLES.

SPECIFICATION forming part of Letters Patent No. 714,697, dated December 2, 1902.

Application filed August 26, 1902. Serial No. 121,069. (No model.)

To all whom it may concern:

Be it known that I, JOSEF HRONECK, a subject of the Grand Duke of Hesse, and a resident of Worms-on-the-Rhine, in the Grand 5 Duchy of Hesse, Germany, have invented certain new and useful Improvements in Apparatus for Coating Metallic Articles, of which the following is a full, clear, and exact description.

10 My invention relates to apparatus for coating metallic articles—such as boxes, pipes, and the like—and has for its object to provide means whereby a uniform coating of paint or similar material may be produced on such 15 articles in a short time for the purpose of protecting such articles against the influence of the weather, of acids, and other injurious substances.

The invention will be fully described hereinafter and the features of novelty pointed out in the appended claims.

An example of my invention is given in the accompanying drawings, in which—

Figure 1 is an elevation of my improved 25 apparatus with parts in section. Fig. 2 is a cross-section thereof, and Fig. 3 is a plan.

It will be understood that my invention is not limited to the specific construction shown, but the scope of the invention is indicated in 30 the appended claims.

As shown, the apparatus comprises a base *a*, upon which rests a support *b*, preferably mounted to rotate about a vertical axis, so that the articles carried by said support may 35 be brought to any convenient position. A tubular support *f* is located centrally—that is, in the direction of the axis about which the plate or table *b* rotates—and this support is provided with a screw-threaded portion 40 upon which is loosely movable an arm *c*, which may be held in any position desired by means of nuts *p*. In the outer ends of the arm *c* are adapted to slide vertically the rods *d* of plungers or holders *d*, which may be provided with 45 an elastic facing, such as a leather facing, at the bottom. The upper portions of the rods *d* are screw-threaded and are engaged by nuts *e*, provided with handles, whereby they 50 may be turned relatively to the arm *c*, while a vertical movement of said nuts is prevented in any suitable manner. To hold the nuts *e*

in position after adjustment, I may employ check-nuts *e'*. The trunnion *b'*, which serves to journal the table or support *b*, is hollow, as shown, and is provided with a partition *s*, 55 which divides the interior of the trunnion into two chambers. The upper chamber communicates with the tubular support *f*, at the top of which is a stuffing-box *l*, connected with a pipe *t* for supplying a heating agent, preferably steam. With the upper chamber of the trunnion *b'* also communicate pipes *g* having valves *o* and leading to nozzles *g'*, which are located above the table or support *b*, the latter being preferably provided with depressions *b*². 60 The nozzles *g'* may, as shown, consist simply of a piece of perforated pipe. From the depressions *b*² pipes *h* lead to the lower chamber of the trunnion *b'*, the connection being controlled by valves *o'*. The lower chamber of 70 the trunnion *b'* further communicates with a pipe *q*, a stuffing-box *k* being provided where this pipe enters the trunnion, and this outlet-pipe *q* is preferably led through a receptacle *m* and is formed with a heating-coil *q'* in said 75 receptacle. This receptacle is adapted to contain the paint or other liquid with which the metallic articles are to be coated.

The articles to be treated are received between the plate or table *b* and the plungers *d*. Preferably washers *n* are placed on the table *b* to engage the lower edges of the articles. I have shown tapering boxes *u*, which, as represented, are placed in the apparatus upside down; but it will be understood that 85 the same apparatus may be used to receive and treat articles open at both ends—such as, for instance, pipes—in which case the plungers *d* would close the upper ends of the articles. In operation, the articles having been 90 placed on the support *b* and fastened thereon by the nuts *e* and plungers *d*, steam or some other heating agent is admitted through the pipe *t*, the hollow standard *f*, the upper chamber of the trunnion *b'*, and pipes *g*, with their 95 nozzles *g'*, into the interior of the articles. The articles then become heated and expand. The steam or other heating agent escapes through the pipes *h* and *q* and heats the paint or other coating substance which is in the receptacle *m*. While the articles are hot the hot coating substance is applied on the out- 100

side of the articles in any suitable manner, as by means of a brush, and, if desired, this operation may be repeated, although, as a rule, one coating will be sufficient. By the 5 use of the valves *o* I am enabled to admit the steam to both articles at the same time or to one of them only, as desired. I consider it best to first admit steam only to one article, then to coat this article exteriorly as described, and then to shut off steam from this article and allow it to pass into the other article. As soon as steam is shut off the cooling of the article and of the coating will cause the coating to solidify, and when the 15 operation is completed the coating will be found to be uniformly applied and its consistency will be like that of rubber or asphalt. I have ascertained that a coating thus applied protects the surface of the article efficiently 20 against the action of the atmosphere and also against stronger influences, as the attack by acids or brine. The procedure hereinbefore described does not take much time, as the cooling which takes place after the shutting 25 off of the steam requires no more than two or three minutes.

I claim as my invention and desire to secure by Letters Patent—

1. In an apparatus of the class described, 30 the combination of a support or base, a table mounted to turn thereon, a nozzle carried by the table, and means for holding an article on the table in such position that the nozzle will be within the article.
2. In an apparatus of the class described, 35 the combination with a base or support, a table mounted to turn on said support, a nozzle carried by the table and means for holding an article in position on the table.
3. In an apparatus of the class described, 40 the combination with a support, of a table mounted to turn thereon and having a hollow trunnion divided into two chambers, a nozzle carried by the table and communicating 45 with one of said chambers, an outlet pipe

or channel connected with the other chamber and leading to the said table, and means for holding an article on the table.

4. The combination of a table having a hollow portion divided into two chambers, a nozzle and a supply pipe or channel for a heating agent connected with one of said chambers, an outlet pipe or channel connected with the other chamber, and means for holding an article on the table adjacent to the nozzle and 50 to one end of the outlet-channel. 55

5. In an apparatus of the class described, the combination of a table provided with a hollow portion divided into two chambers, a supply pipe or channel for a heating agent 60 connected with one of said chambers, a nozzle arranged adjacent to the table and connected with the same chamber, a discharge channel or pipe connected with the table and with the other chamber, a vessel for containing paint or other coating material, and an outlet-channel leading from the last-named chamber through the said vessel. 65

6. In an apparatus of the class described, the combination with the support or base, of 70 a table carried thereby and provided with a vertical trunnion about which it is adapted to rotate, said trunnion being hollow and being divided into two chambers, a tubular standard connected with the upper chamber 75 of the trunnion, means adjustably carried by said standard for holding an article between said means and the table, a nozzle carried by the table and in communication with the upper chamber of the trunnion, and a discharge 80 pipe or channel connected with the table and leading to the lower chamber of the trunnion.

In witness whereof I have signed my name to this specification in the presence of two subscribing witnesses.

JOSEF HRONECK.
